PORTABLE RADIO CABINET

John W. Mason, Detroit, Mich.

Application April 4, 1956, Serial No. 40,893

Term of patent 14 years

(Cl. D56—4)

Fig. 1.

Fig. 4.

Fig. 3.

Fig. 2.

Fig. 1 is a front perspective view of a portable radio cabinet showing my new design;

Fig. 2 is a rear perspective view of the portable radio cabinet with the pop-out antenna being turned to a desirable signal receiving position;

Fig. 3 is a bottom view of the portable radio cabinet; and

Fig. 4 is a sectional view along line 4—4 of Fig. 1.
I claim:

The ornamental design for a portable radio cabinet, as shown and described.
